UNITED STATES PATENT OFFICE.

HERBERT J. HOLMES, OF NEW YORK, N. Y.

MEANS FOR SECURING METAL TRIMMINGS OR MOLDINGS TO DOOR AND OTHER FRAMES.

1,068,656.

Specification of Letters Patent.

Patented July 29, 1913.

Application filed April 29, 1913. Serial No. 764,469.

To all whom it may concern:

Be it known that I, HERBERT J. HOLMES, a citizen of the United States, and residing in the Bronx, New York, in the county of 5 New York and State of New York, have invented certain new and useful Improvements in Means for Securing Metal Trim- 10 mings or Moldings to Door and other Frames, of which the following is a specifi- 15 cation, such as will enable others skilled in the art to which it appertains to make and use the same.

This invention relates to what are known as metal trimmings or moldings used in 15 connection with door and other frames, and the object thereof is to provide improved means for securing such trimmings or moldings to a frame without the use of nails, screws, or similar devices, as heretofore.

20 The invention is fully disclosed in the following specification of which the accompanying drawing forms a part, in which the separate parts of my invention are designated by suitable reference characters 25 in each of the views, and in which:

Figure 1 is a transverse sectional view of one side portion of a door frame and showing part of a door, and showing the metal trimmings or moldings for said frame in 30 cross section and my improved means for locking or securing the same to the frame, on the line 1—1 of Fig. 2;—Fig. 2 a view looking in the direction of the arrow 2 of Fig. 1 with part of the construction broken 35 away;—Fig. 3 an inside view of a binding lever which I employ showing the same detached and looking in the direction of the arrow 3 of Fig. 1, and;—Fig. 4 a modification of a detail shown in Fig. 1.

40 In the drawing forming part of this specification I have shown at *a* one side of a door frame and at *b* a part of a door, and I have also shown at *c* and *d* two metal trimmings or moldings which are approximately 45 L-shaped in cross section, together with my improved means for securing said metal trimmings or moldings to the frame.

The metal trimmings or moldings *c* and *d* comprise face portions *c*² and *d*² and side 50 portions *c*³ and *d*³, and in the construction shown the face portions *c*² and *d*² abut at *e*, and the part *c*² is provided with a vertical buffer strip *f* against which the door *b* abuts or strikes when said door is closed, and 55 this part *f* is box-shaped in form in cross

section and is secured to the part *c*² by rivets *f*² or otherwise. The part *c*² is also provided on the inner side thereof with a reinforcing strip *g* having a flange portion *g*² which extends beyond the abutting point *e* of the parts *c*² and *d*² and to which the part *d*² is secured by a screw or screws *g*³. I also provide two binding levers *h* and *i* having face arms *h*² and *i*² and side arms *h*³ and *i*³ and which are placed on the inner 60 sides of the strips or moldings *c* and *d*, transversely thereof, and secured thereto at *j*.

The levers *h* and *i* are reinforced in the angles thereof, in the form of construction shown, by transverse or diagonal brace 70 members *j*² and the side arm portions *h*³ and *i*³ of said levers are secured to the parts *c*³ and *d*³ of the strips or moldings *c* and *d* at *j*³, and the ends of the parts *h*² and *i*² of 75 said levers are slotted longitudinally, as shown at *k*.

In the form of construction shown, I secure to the face of the door frame member *a* a vertically arranged strip *k*² provided with a transverse recess *k*³, and the levers *h* and *i* 80 are so arranged on the strips or moldings *c* and *d* that when said moldings are placed in position one of said levers will be slightly above the other, as shown in Fig. 2, and passed outwardly through the parts *c*² and *d*² of 85 *g* of the strip or molding *c* are screws *m*.

In practice, the strip or molding *c* with the parts all assembled including the screws *m*, is first placed in position and one of the screws *m* passes into the slot *k* in the end 90 of the part *h*² of the lever *h* after which the other strip or molding *d* is slid into position and the other screw *m* passes into the slot *k* in the end portion *i*² of the lever *i*.

The screws *m* are provided with trans- 95 verse grooves or recesses *m*² in their outer ends, and with the parts assembled in the manner described, the screws *m* may be turned so as to draw the arms *h*³ and *i*³ of the levers *h* and *i* inwardly, and press the 100 parts *c*³ and *d*³ of the strips or moldings *c* and *d* closely against the opposite sides of the door frame member *a*, after which a molding strip *n* is placed in position, as shown in Figs. 1 and 2, and this strip covers 105 the connections between the parts *c*² and *d*² and the screws *m* and forms a finish on the side of the part *f* opposite that against which the door *b* strikes or abuts when 110 closed.

The molding strip n is provided with a face member n^2 which abuts against the part f and in which is a longitudinal groove n^3 forming on the inner side thereof a corresponding longitudinal bead, and hook devices o are secured on the outer surfaces of the part c^2 and operate in connection with the said bead to hold the molding strip n in position, and the operation of these parts in locking said strip in position is automatic.

The arms h^3 and i^3 of the levers h and i are provided with one or more prongs p designed to enter the door frame member a and to prevent the molding strips c and d from slipping, and said arms h^3 and i^3 of the levers h and i are preferably reinforced at these points by blocks p^2 which form backings therefor and also for the parts c^3 and d^3 of the moldings c and d .

Instead of using the prongs p , I may employ studs p^8 one of which is shown in Fig. 3, if, it be desired to form the door frame member a of metal, in which case, the said metal will be bored to receive the studs p^8 .

In the construction shown, the levers h and i are composed of sheet metal bent into form and reinforced, but these levers may be cast, if desired, or may be made in any preferred manner, and if necessary the corners of the door frame may be cut away, as indicated by the dotted lines x , in order to provide more room for said levers and in order that they may be made of heavier metal and of different form if desired.

In the construction shown, the door frame member a is supposed to be made of wood, but, it will be understood, that the door frame may be made of metal or in any desired manner, and various changes in and modifications of the construction herein described may be made, within the scope of the appended claims without departing from the spirit of my invention or sacrificing its advantages.

The screws g^8 pass into the strip k^2 and other screws r may be employed to secure the part c^2 of the molding c to the strip k^2 , but these screws are not essential and may or may not be employed; and changes in and modifications of the construction herein shown and described may be made, within the scope of the appended claims, without departing from the spirit of my invention or sacrificing its advantages, and in Fig. 4 I have shown a modification in which I substitute for the screw or screws m , another form of screw m^3 having a head m^4 inwardly of which is an annular groove m^5 , and in this view, the arm h^2 of the lever h is shown, and with this form of screw substituted for the screw or screws m , said screw or screws, when turned in one direction, will force the arms h^2 and i^2 of the

levers h and i inwardly and the arms h^3 and i^3 outwardly so as to detach or loosen the molding strips c and d , and when said screws are turned in the opposite direction, the arms h^2 and i^2 of said levers will be drawn outwardly and the arms h^3 and i^3 inwardly so as to hold said molding strips in position.

Having fully described my invention what I claim as new and desire to secure by Letters Patent is:—

1. The herein described means for securing angular metal strips or moldings to frames, said metal strips or moldings consisting of face portions and side portions, said means consisting of L-shaped levers placed on the inner sides of said strips or moldings transversely thereof and comprising face arms and side arms, said levers being secured in the angles of said strips or moldings and to the side portions thereof, and means for drawing the face arms of said levers outwardly into close connection with the face portions of said strips or moldings.

2. The herein described means for securing angular metal trimming strips or moldings to door or other frames, said strips or moldings being substantially L-shaped in cross section, said means consisting of L-shaped levers secured in the inner sides of said strips or moldings transversely thereof, one end portion of said levers being secured to the corresponding parts of said strips or moldings and the other left free, and means for drawing the free end portions of said levers outwardly into contact with the corresponding parts of the strips or moldings.

3. The herein described means for securing angular metal trimming strips or moldings to door or other frames, said strips or moldings being substantially L-shaped in cross section, said means consisting of L-shaped levers secured in the inner sides of said strips or moldings transversely thereof, one end portion of said levers being secured to the corresponding parts of said strips or moldings and the other left free, and means for drawing the free end portions of said levers outwardly into contact with the corresponding parts of the strips or moldings consisting of longitudinal slots in the ends of said parts of said levers, and screws passed therethrough and outwardly through the said parts of said strips or moldings.

4. The herein described means for securing angular metal strips or moldings to door frames, said metal strips or moldings being substantially L-shaped in cross section and consisting of face portions and side portions, said means consisting of L-shaped levers placed on the inner sides of said strips or moldings transversely thereof and comprising face arms and side arms, the side arms being secured to the side portions of

said strips or moldings and the face arms being left free, and means for drawing the face arms of said levers outwardly into close connection with the face portions of said strips or moldings, and the face portions of one of said strips or moldings being provided with an abutting member against which the door strikes when closed, and the connections of the face portions of said strips or moldings being covered by a detachable molding strip placed at the side of

the said abutting member opposite that against which the door strikes.

In testimony that I claim the foregoing as my invention I have signed my name in presence of the subscribing witnesses this 26th day of April 1913.

HERBERT J. HOLMES.
